William H. Fulper Inventor
By his Attorney Frank J. Kent

UNITED STATES PATENT OFFICE.

WILLIAM H. FULPER, OF FLEMINGTON, NEW JERSEY.

RECEPTACLE.

Application filed October 22, 1926. Serial No. 143,456.

This invention relates to receptacles. The invention more particularly has in mind to provide a new and improved combination of receptacle and mount, wherein 5 various dissimilar materials are used for receptacle and mount parts in such manner that the respective properties of said materials will usefully coact rather than otherwise.

10 The invention, as preferably carried out, provides the combination of a receptacle which is cup or vase shaped and which is made of pottery or some similar characteristically brittle material; a suspensory 15 device for the receptacle including a spike, prong equipment of the stick-pin type, and consequently of metal or some similar characteristically tough and non-brittle material; and a means for securing the prong 20 equipment to the receptacle and constituting a structure or collection of material having properties unlike those of the materials of either the receptacle or the prong equipment.

25 One of the objects of the invention is to provide a receptacle of the material indicated, and equipped with a novel suspensory means whereby the receptacle may be readily attached to and detached from any 30 one of the various elements of a room's furnishings or furniture of the kind which may be readily pierced by a downwardly directed stick-pin or the like. Such an element capable of thus being pierced would 35 be, for example, a piece of wall drapery, or the fabric-covered arm or back of an upholstered chair. The new article of manufacture thus provides a receptacle which may be used for widely diversified purposes.

40 It may be employed, for instance, as an ash receiver, or as a vase for cut flowers, or as a condiment holder.

Another object is to provide a receptacle of the material indicated, and yet one 45 equipped with a prong means secured to the receptacle near its upper end, such prong means including a prong member dependent on the outside of the receptacle, and this prong member being of metal and terminating at its lower end in a point, whereby a simple downward movement of the whole device securely hangs it in place and a simple upward movement detaches the same.

50 Another object is to provide a connection for the upper end of the prong member or members whereby such member or members

may be readily and inexpensively joined to the receptacle, but at the same time really permanently anchored thereto, even with receptacle and prong equipment of such widely dissimilar materials as say porcelain and 60 steel or spring brass.

The invention will be more clearly understood from the following description, when taken in connection with the accompanying 65 drawing, which illustrates several of the many possible forms which the invention may take. These illustrated forms, while some of them are now preferred, represent merely present preferences; and of course 70 the scope of protection contemplated is to be taken solely from the appended claims.

In this drawing;

Fig. 1 is a perspective view showing a vase-like receptacle, equipped with a single 75 prong according to the invention.

Fig. 2 is a fragmentary view showing the flat back-wall of the receptacle of Fig. 1 in section, and showing similarly the attaching means for the head of the prong;

Fig. 2^a is a perspective view of the prong shown in side elevation in Fig. 2; and

Figs. 3, 4, 5 and 6 are views generally similar to Fig. 2, but indicating different arrangements for facilitating a secure connection of prong equipment and receptacle. In each of these views, also, a single-pin 80 prong equipment is illustrated.

Similar reference characters refer to similar parts throughout the several views.

Referring to Figs. 1, 2, and 2^a, the receptacle is indicated at 7. The back-wall thereof, 7^a, in the present case flat or plane, is provided on its outside and near its top with a recess 8 large enough to receive the 95 enlarged head of a prong element 9 and then to have poured, tamped or otherwise trapped therein a collection of material within which the head of the element 9 will be imbedded. This material is indicated at 100 10, and desirably is solder or the like. Material 10 should be a material having certain properties, when squeezed into tight engagement with recess 8, especially when secured in place in the recess by pouring 105 said material into the recess and then allowing the material to harden and set in situ around the head of the prong element. The material should have a fairly low melting point, to avoid too great heat shock to 110 the receptacle. Also, the material should have considerable toughness when in the

solid state. Again, it may well have a natural affinity for the material of which the prong element is made; which would be the case were said element of brass, and were 5 the anchoring material ordinary solder. Further, it is highly desirable that the anchoring material have ready fluidity when molten, so as to shape itself closely to the tiny surface irregularities, indentations, &c. 10 present in recess 8 when the receptacle 7 is of pottery.

The recess 8 may be of any suitable shape, but it is recommended that the outline of the same at wall 7^a be other than circular. 15 Desirably, such outline is polygonal rather than rounded, so as to present corners as shown in Fig. 1. A properly designed recess has much to do with the coaction of material 10 and the material of which the receptacle 7 is formed, in reliably anchoring 20 the prong element 9 in the recess and to the receptacle.

The prong-element 9 where only one such is used, as in the embodiments of the invention shown in all the views, is preferably shaped at its head so as to lock the element against swing in any plane relative to the material 10. In the present case, the prong element is provided with a T-head, as clearly 30 shown in Fig. 2^a.

Referring now to the forms shown in Figs. 3 to 6, variously shaped and located recesses are shown, as further illustrative of divers ways in which the invention may be embodied, even in the case of the vase 7 in Fig. 1, and even with the prong equipment limited to a single stickpin element such as the one shown in Fig. 2^a.

The arrangements of Figs. 3, 4 and 5 are 40 similar to those of Figs. 1 and 2 in the respect that the recesses 8 are provided with opposed side walls which are inclined away from each other toward the bottoms of the recesses; to give each recess a dove-tail shape, the better to hold in place the material 10.

In Fig. 3 the recess 8 is shown practically in the same location as that of Fig. 2. In Fig. 3, however, the recess 8 is shown as being longer from top to bottom. This permits the prong element 9 to be mounted in place, and thereafter to be used, according to the invention, but without requiring the upper portion thereof, corresponding to the 50 part marked 9' in Fig. 2^a, to be bent as shown in Fig. 2^a.

The forms of Figs. 2 and 3 have thus one other point in common, that the piercing length of element 9 depends below the recess 60 8 at an angle to the plane of wall 7^a.

The forms of Figs. 4 and 5 differ from those of Figs. 2 and 3 in that the receptacle carries on its outside and at or near its top a canopy or transverse rib, as indicated at 65 11, in the underside of which is formed the

recess 8. Figs. 4 and 5 differ from each other in that the recess in the latter is located closer to the back-wall 7^a of the receptacle, and consequently the canopy 11 may be made of less width, as shown. In both 70 Figs. 4 and 5, then, the prong-element 9 may be mounted in place, and thereafter used, according to the invention; yet with the element unbent, and at the same time with its piercing length depending parallel to the 75 plane of the back-wall 7^a. In Fig. 5, however, the element is fairly close to the back-wall throughout the length of the former.

The forms of Figs. 4 and 5 are at present preferred over the forms of Figs. 2 and 3, 80 because apparently in the case of the former, the element 9 is more securely connected to the receptacle by way of the material 10; the anchorage of the element being particularly resistent to any accidental tendency of the 85 element 9 to act as a pry-bar on material 10, due to flexings or springings of the element during use of the device.

Referring finally to the form shown in Fig. 6, which is similar to the forms of Figs. 4 and 5 in that the canopy 11 is present, and so the piercing length of element 9 may depend parallel with back-wall 7^a if desired, this form of Fig. 6 is at present preferred 90 over even the forms of Figs. 4 and 5, for the 95 following reasons. In Fig. 6 the canopy is provided with a T or L-shaped recess as shown. In other words, two recesses are employed, one at an angle to, and opening into, the other. In the present case, the upper recess is horizontal, as indicated at 8^a, and the lower recess is vertical, as indicated at 8^b.

Thus the recesses 8^a and 8^b may be circular in cross-section; and this would be true, even if the lower recess opened into the upper recess at rather than slightly removed from the inner end of the latter. These recesses 100 may be round, as just stated, and for greater ease of making, because the material 10 in each recess would lock against any movement whatever the material in the other recess.

This would be a mutual keying action between all parts of the material 10; since this material, according to the invention, is a single rigid mass on each device. Not only could each recess be circular in cross-section, 110 as just stated, but neither recess would have to be undercut. Indeed, each recess could have slightly conical walls flaring outwardly, which would facilitate manufacture; yet the mutual keying action above referred to, 120 would nevertheless be present. Finally, where the two angularly related recesses are so disposed that the lower one is open at its bottom, as is the recess 8^b of Fig. 6, this recess could be made of considerable length, 125 as also shown in Fig. 6. And then the prong element could be merely, as further shown in Fig. 6, an ordinary "bank-pin" 9^a of, or magnified to, the proper size.

While I have taken great pains to show and carefully explain a number of different forms or embodiments of the invention, and while I have mentioned certain uses, and certain materials, and certain preferences as between various of such embodiments, it is of course to be understood that these are not to be taken as in any way defining or limiting the invention itself. Various changes may be made in what has been shown and described, and many apparently widely different embodiments may be devised, yet all to fall within the scope of the invention as defined in the following claims.

15 I claim:

1. The combination of a receptacle having a recess, a prong element having a depending piercing length and an upper end portion shaped to fit loosely in said recess, and an anchoring means wedged in the recess and about the upper end portion of the prong element.
2. A receptacle carrying a depending prong element, and means for securing the prong element at its upper end to the upper end of the receptacle, the receptacle having a recess forming a part of said means, said means also including an enlarged head on the element and a collection of material cast in situ in said recess to embed the enlarged head of the element in said material.
3. A receptacle, and suspensory means thereof, said means including a depending prong element with a piercing point at its lower end and also including a collection of material within which the upper end of the prong element is embedded and which is secured to the receptacle, the receptacle being of a brittle material such as pottery.
4. A receptacle of a brittle material such as pottery, said receptacle having a recess in its outer portion near its top, a prong element of a less brittle material than pottery, and a collection of material tight in said recess and secured tight around the end

portion of said element remote from its piercing point.

5. As a new article of manufacture, a stick-on pottery receptacle, said receptacle having a recess, the stick-on means including a depending prong element, there being a mounting means for the upper end portion of the prong element, said mounting means including a collection of material different from the material of which the receptacle is made and also different from the material of which the prong element is made, said material being wedged into said recess and engaging the prong element to hold the upper end portion thereof rigid relative to the receptacle.

6. A pottery receptacle having on its outside a canopy and having in said canopy an undercut recess, a prong element the upper end of which is inserted into said recess, and a collection of material wedged in said recess and within which is embedded the upper end of the prong element.

7. A pottery receptacle having a recess presenting a mouth at the outside of the receptacle, a depending prong element, and a collection of material in the recess, the upper end of the prong element being embedded in said material, said recess being shaped to deviate from a circular cross-section at least for a part of its length to prevent the material from being loosened in the recess by strains transmitted through the prong element.

8. A pottery receptacle having on its outside a canopy, and having in said canopy an upwardly extending recess and a recess outwardly extending from the first recess to the outer edge of the canopy, a depending prong element the upper end portion of which is extended into the first recess, and a single collection of material in both recesses and surrounding the part of the prong element extended into the first recess.
